THOMAS McCHEYNE GUNN, OF NEW LONDON, CONNECTICUT, ASSIGNOR TO ELECTRIC BOAT COMPANY, OF NEW YORK, N. Y., A CORPORATION OF NEW JERSEY.

TORPEDO-LAUNCHING APPARATUS.

1,097,623.

Specification of Letters Patent. Patented May 26, 1914.

Application filed November 30, 1912. Serial No. 734,317.

To all whom it may concern:

Be it known that I, THOMAS McCHEYNE GUNN, a citizen of the United States, residing at and whose post-office address is New 5 London, county of New London, and State of Connecticut, have invented certain new and useful Improvements in Torpedo-Launching Apparatus; and I do hereby declare the following to be a full, clear, and exact 10 description of the invention, such as will enable others skilled in the art to which it appertains to make and use the same.

The present invention relates to operating mechanism for clearing the line of fire of a 15 torpedo tube which is arranged lengthwise of a boat in line with a retractable section of the hull near the bow or stern, and more specifically to apparatus of this kind wherein the normally closed cap of the torpedo 20 tube and the normally closed retractable hull section of the boat are simultaneously opened in a single driving operation so as to permit of quickly firing the torpedo contained in the torpedo tube.

This apparatus is particularly applicable 25 to submarine boats and the like where it is desirable that the torpedo tubes be mounted within the boat. In such arrangements, it is also desirable that the hull of the boat 30 have fine lines and smooth lines without substantial interruption so as to lend itself to high speed and rapid diving possibilities in warfare as well as in runs of duration. And inasmuch as the favorable opportunity 35 in warfare for firing torpedoes occurs quickly and without much warning, so that deliberate preparation for such actuation is found impossible, and, furthermore, since the favorable opportunity quickly disappears each time, it is of utmost importance 40 to the highest efficiency of action that the necessary preparation for firing torpedoes be reduced to the simplest operation and to the shortest period required to deliver the fire.

All of these prerequisites are nicely attained 45 in the arrangement herein disclosed, where there is provided a retractable section forming a part of the hull in such manner as to give fine lines and smooth lines thereto, associated with operating mechanism for the 50 retractable section adapted to retract it from its normally closed position to its open position and to simultaneously open the normally closed cap of the torpedo tube to completely 55 clear the line of fire of the torpedo tube in

a single driving operation. Usually a plurality of such torpedo tubes are provided on a boat, and in this case the simplicity and directness underlying the idea embodied in the entire arrangement is preserved by providing a separately retractable hull section for each torpedo tube and by maintaining the operating mechanism for each torpedo tube separate from each of the others and independently operable.

In the accompanying drawings, illustrating the forward part of a submarine boat, wherein my improved arrangement is shown with several modified forms of construction of the operating devices therefor, Figure 1 70 shows the vertical arrangement of the torpedo tubes, the arrangement being similar on both sides of the boat. Fig. 2 is an enlarged sectional plan on line 2—2 of Fig. 1, showing the operating mechanism for the 75 upper torpedo tubes on the two sides of the boat; and Fig. 3 is an enlarged sectional elevation, partly broken away, on line 3—3 of Fig. 2, showing modified forms of operating mechanisms, although it is to be understood 80 that it is proposed to use only one form of construction throughout any boat, that one depending upon various conditions existing in the boat.

The fine lines of the bow of the boat 85 adapting it for speed in running and diving are indicated particularly in Fig. 2, wherein 1 indicates the rigid parts, and 2 the separately retractable sections, each of which is pivoted at 3 so as to swing inwardly and laterally from the normally closed position indicated in full lines, in which position the smooth hull lines are not substantially interrupted. Directly in longitudinal line with the opening produced upon retracting each 90 retractable section and to the side of the longitudinal center line of the boat, is rigidly mounted a torpedo tube 4 arranged lengthwise of the boat so as to fire substantially in the direction of motion. Each of 100 these torpedo tubes is provided with a cap 5 normally closed over the forward end thereof. In order to retract any of the retractable hull sections 2 and to simultaneously open the cap 5 of the corresponding torpedo tube 4, there is provided an operating mechanism comprising a shaft 6, suitably journaled for turning, and a toothed segment 7 fastened on the shaft in driving engagement with the worm 8, which is driven 110

in any suitable way. Several forms of positive operating connections from the shaft 6 to the retractable hull section 2 and to the torpedo cap 5 are shown in Fig. 3, but in all 5 of these there is a member 9 fastened to the shaft 6 and having a rigid branch 10 extending to a connection 11 on the cap 5, and a collapsible branch comprising a rigid member 12 having a pivoted connection at 10 13 with a member provided with a turnbuckle 14 and a pivoted connection at 15 with the retractable hull section 2. The connection to the retractable hull section may comprise one collapsible branch, as 15 shown in the upper part of Fig. 3, or two collapsible branches closely embracing the rigid branch 10, as shown in the lower right-hand part of Fig. 3, or widely embracing it as shown in the lower left-hand part of Fig. 20 3. In all cases the actuation of each operating mechanism is intended to be independent of each of the others, so that any one of the shafts 6 may be turned to its open position to retract the retractable hull section 2 25 and simultaneously open the cap 5 of the corresponding torpedo tube 4, and may thereafter be turned to its closed position to restore these parts to their normal positions as shown in the full lines of Fig. 2. The 30 broken lines in Fig. 2 show the position of the parts when the shaft 6 is turned to its open position, whereupon the line of fire of the corresponding torpedo tube is cleared for the expulsion of the torpedo 16 contained therein, in any suitable way.

It is intended in all the arrangements shown, that the operating connections be so arranged as to give a powerful leverage on the retractable hull section near its normally 40 closed position, just as would be obtained in the case of a toggle joint. Furthermore, when the retractable hull section is completely closed, the parts of the collapsible operating arm then form a slight angle in 45 such direction that any pressure or blow on the retractable hull section tends to hold the cap in its closed position on the torpedo tube, but without more than a slight pressure, as is best indicated by the full lines in 50 Fig. 2.

By the arrangement hereinbefore described, the line of fire of each torpedo tube is cleared positively and quickly by apparatus intended to be simple and direct in operation, whereby in warfare a favorable opportunity for firing may be quickly availed of without undue preliminary preparation. Furthermore fine hull lines are attained by this arrangement, and in this connection it 55 is to be understood that my improvements may be similarly applied to the stern of the boat to give fine lines thereat when it is desired to provide for firing torpedoes rearwardly, which is likewise important since it 60 is essential to the promotion of speed that 65

this portion of the hull conform to such outline also.

Having thus described my invention, what I claim is:—

1. The combination with a boat having a normally-closed laterally-retractable hull section near one end and to the side of the longitudinal center line of the hull, and a torpedo tube provided with a normally-closed cap and mounted entirely within the hull of the boat lengthwise thereof in firing line with the opening produced in the hull upon retracting the retractable hull section, of operating mechanism for clearing the line of fire of the torpedo tube by a single driving operation, comprising a driving connection, and positively-connected operating mechanism driven by the driving connection and connected to both the retractable hull section and to the torpedo cap in such manner as to retract the retractable hull section and to simultaneously open the cap upon operation of the driving connection to its open position, said retractable hull section normally conforming to the hull lines of the boat; substantially as described.

2. The combination with a boat having a normally-closed retractable hull section near one end, and a torpedo tube provided with a normally-closed cap and mounted within the boat lengthwise thereof in firing line with the opening produced in the hull upon retracting the retractable hull section, of operating mechanism for clearing the line of fire of the torpedo tube by a single driving operation, comprising a driving connection, an operating connection extending to the cap of the torpedo tube and actuated by the driving connection, and a collapsible operating connection extending to the retractable hull section and actuated by the driving connection, the arrangement being such that when the retractable hull section is in its normally-closed position pressure on it is transmitted to the cap of the torpedo tube in a direction to hold it to its closed position; substantially as described.

3. The combination with a boat having a normally-closed laterally retractable hull section near one end and to the side of the longitudinal center line of the hull, and a torpedo tube provided with a normally closed cap and mounted entirely within the hull of the boat lengthwise thereof in firing line with the opening produced in the hull upon retracting the retractable hull section, of operating mechanism for clearing the line of fire of the torpedo tube by a single driving operation, comprising a rotatable shaft, means for turning said shaft, an operating connection between the shaft and the cap of the torpedo tube, and an operating connection between the shaft and the retractable hull section, the arrangement being such that by turning said shaft to its open position the

- retractable hull section is retracted and the cap is simultaneously opened, said retractable hull section normally conforming to the hull lines of the boat; substantially as described.
4. The combination with a boat having a normally-closed retractable hull section near one end, and a torpedo tube provided with a normally-closed cap and mounted within the boat lengthwise thereof in firing line with the opening produced in the hull upon reTRACTING the retractable hull section, of operating mechanism for clearing the line of fire of the torpedo tube by a single driving operation, comprising a driving gear, a rotatable shaft, a toothed segment fastened on said shaft in driving engagement with said gear, a lever coupled to said shaft and operatively connected to the torpedo cap, and a collapsible connection coupled to said shaft and operatively connected to the retractable hull section, the arrangement being such that by turning said shaft to its open position the retractable hull section is retracted and the cap is simultaneously opened; substantially as described.
5. The combination with a boat having a normally-closed retractable hull section near one end, and a torpedo tube provided with a normally-closed cap and mounted within the boat lengthwise thereof in firing line with the opening produced in the hull upon reTRACTING the retractable hull section, of operating mechanism for clearing the line of fire of the torpedo tube by a single driving operation, comprising a driving connection, a torpedo cap operating connection actuated by the driving connection, and a jointed operating connection for the retractable hull section, the arrangement being such that a powerful leverage is produced on the retractable hull section when near its normally closed position; substantially as described.
6. The combination with a boat having a normally-closed retractable hull section, and a torpedo tube provided with a normally-closed cap and mounted in firing line with the opening produced in the hull upon reTRACTING the retractable hull section, of operating mechanism for clearing the line of fire of the torpedo tube by a single driving operation, comprising a driving connection, a torpedo cap operating connection actuated by the driving connection, and a jointed operating connection for the retractable hull section, the arrangement being such that a powerful leverage is produced on the retractable hull section when near its normally closed position; substantially as described.

In testimony whereof I affix my signature, in presence of two witnesses.
